Attorneys.

UNITED STATES PATENT OFFICE.

HARRY W. NEAL, OF INDIANAPOLIS, INDIANA, ASSIGNOR TO HALL-NEAL FURNACE COMPANY, OF INDIANAPOLIS, INDIANA.

FURNACE BASE.

Application filed March 7, 1929. Serial No. 344,942.

This invention relates to house heating furnaces and particularly to the base of such furnaces. Heretofore, furnaces have been commonly mounted on a cast iron spider 5 having an outer ring to support the furnace wall and a plurality of bars extending integrally therefrom to an inner ring fitted around the base of the ash pit. Most floors, usually basement floors, are uneven and in levelling up the ring, blocking would be placed under the low side of the ring, with the result that lack of uniform support under the ring would cause the cast iron ring to crack or break and permit air to enter within the furnace wall carrying coal or ash dust along with it. Furthermore, such rings were exceedingly difficult to pack and ship about the country and a great loss in breakage was occasioned due to their inherent fragile nature.

By my invention, I overcome these difficulties, and not only provide a rigid non-breakable base but also provide means permitting the quick aligning of the ash pit in relation to the ring and in anchoring the ash pit to one side of the ring to permit the pit to expand and contract at will therefrom without causing any liability of breakage of the support thereunder.

In describing the invention, reference is made to the accompanying drawing, in which—

Fig. 1 is a fragmentary side elevation of a furnace embodying the invention;

Fig. 2, a horizontal section on the line 2—2 in Fig. 1;

Fig. 3, a vertical section on the line 3—3 in Fig. 2;

Fig. 4, a vertical section on the line 4—4 in Fig. 2;

Fig. 5, a detail in top plan view of the front section of the base ring; and

Fig. 6, a vertical section through the base ring.

Like characters of reference indicate like parts throughout the several views of the drawing.

I roll a length of T-bar 10 to form substantially a circular ring with the leg 11 of the bar extended vertically therefrom,

and between the ends of the bar 10, I fix therebetween preferably by welding, a length of Z-bar 12 to have its vertical leg abut by its ends the ends of the vertical leg 11 of the bar 10, and to have its lower horizontal flange projecting forwardly in the plane of the base of the bar 10. The upper horizontal leg of the Z-bar 12 projects rearwardly with its top face in the plane of the top edge of the leg 11. Each end of this top horizontal leg of the Z-bar terminates in an up-turned lug 13, Figs. 2, 4 and 5.

I preform four bars 14 to have their ends bent backwardly 135 degrees from the bars and then arrange these bars 14, as in Fig. 2 to have the bent ends contact one another so as to define a square by the bars and weld the ends together over the area of contact to form a unitary spider which is positioned on the formed T-bar 10 from the top side to have one pair of the bar ends coming under the center of the top horizontal flange of the Z-bar 12, Fig. 2, and the ends of the other pairs of the bent bar ends contacting the T-bar leg 11 at intervals of 90 degrees therearound to position the square defined by the bars 14 diagonally in reference to the Z-bar 12. The bar ends are welded to the T-bar 10.

The ash-pit 15 of the furnace is circular with a projecting rectangular passageway 16 extending therefrom to the ash-pit door 17.

The ash-pit 15 has a centering mark 18 on its rear side and is set upon the bars 14 whereby the line of contact of the two rear-most bar ends if extended would pass through the mark 18, and the front edge of the passageway 16 is brought forward to coincide with the top forward edge of the vertical leg of the Z-bar 12 to have the passageway drop in between the two lugs 13.

A length of angle-iron 19 is welded to the top face of the lower horizontal flange of the Z-bar 12 at its forward edge to a slot 95 between the angle-iron and the vertical leg of the Z-bar 12. A door frame 20 has its lower end entered into this slot and is secured to flanges 21 of the ash-pit passageway 16 by means of bolts whereby the ash-

pit is relatively located and secured in position with respect to the ring formed by the T-bar 10.

The T-bar 10 may be leveled on the supporting floor 22, in Fig. 6, and cement 23 applied around its inner side to form an air seal therebetween. The wall 24 of the furnace is fitted around the bar 10 to rest thereon and bear against the leg 11, the rolled T-bar 10 having a smooth even surface whereby the wall may be snugly united thereto.

I claim:

1. In a furnace, a base bar having an inverted T-section being formed to define the shape of the furnace wall and having its ends brought around and directed toward each other, a Z-bar interposed and secured between the ends of the base bar to have the upper flange of the Z-bar directed horizontally inwardly, up-turned lugs at the ends of said upper flange, and a built up spider mounted within and secured to said base bar.

2. In a furnace, a base bar having an inverted T-section being formed to define the shape of the furnace wall and having its ends brought around and directed toward each other, a Z-bar interposed and secured between the ends of the base bar to have the upper flange of the Z-bar directed horizontally inwardly, up-turned lugs at the ends of said upper flange, and a built up spider mounted within and secured to said base bar, an ash-pit resting on the spider, and a door-frame having its lower end contacting the forward side of said Z-bar and secured to said ash-pit.

3. In a furnace, a base bar having an inverted T-section being formed to define the shape of the furnace wall and having its ends brought around and directed toward each other, a Z-bar interposed and secured between the ends of the base bar to have the upper flange of the Z-bar directed horizontally inwardly, up-turned lugs at the ends of said upper flange, and a built up spider mounted within and secured to said base bar, an ash-pit resting on the spider, and a door-frame having its lower end contacting the forward side of said Z-bar and secured to said ash-pit, said Z-bar having a slot formed on its lower forwardly projecting flange to receive the lower end of said door-frame therein.

4. In a furnace, a base comprising a mounting ring having an inverted T-section, a plurality of preformed bars having their ends united one to the other and secured to and supported by said ring, and a straight section in said ring defining the front of the furnace.

5. In a furnace, a base comprising a mounting ring having an inverted T-section, a plurality of preformed bars having

their ends united one to the other and secured to and supported by said ring, and a straight section in said ring defining the front of the furnace, said bars defining an open rectangle therebetween and positioned to have a diagonal thereof normal to the center of said straight section.

6. In a furnace, a base comprising a mounting ring having an inverted T-section, a plurality of preformed bars having their ends united one to the other and secured to and supported by said ring, and a straight section in said ring defining the front of the furnace, said straight section being formed by a length of Z-bar interposed and secured between the ends of said ring to have a top horizontal flange extending therefrom inwardly from the vertical face of the bar.

7. In a furnace, a base comprising a mounting ring having an inverted T-section, a plurality of preformed bars having their ends united one to the other and secured to and supported by said ring, and a straight section in said ring defining the front of the furnace, said straight section being formed by a length of Z-bar interposed and secured between the ends of said ring to have a top horizontal flange extending therefrom inwardly from the vertical face of the bar, a lower horizontal flange projecting forwardly therefrom and an angle-bar spaced forwardly from the face of said bar and secured to said lower flange, and up-turned lugs on the ends of said upper horizontal flange.

In testimony whereof I affix my signature.

HARRY W. NEAL.
